UNITED STATES PATENT OFFICE.

SOPHIE F. ROSE, OF CHICAGO, ILLINOIS.

DESIGN FOR A SACHET-BAG.

48,992.

Specification for Design.

Patented May 2, 1916.

Application filed January 21, 1916. Serial No. 73,475. Term of patent 3½ years.

To all whom it may concern:

Be it known that I, SOPHIE F. ROSE, a citizen of the United States, residing at Chicago, in the county of Cook and State of Illinois, have invented a new, original, and ornamental Design for Sachet-Bags, of which the following is a specification, reference being had to the accompanying drawing forming part hereof.

The drawing is a plan view of a sachet bag showing my design.

I claim:

The ornamental design for a sachet bag, as shown.

SOPHIE F. ROSE.
